UNITED STATES PATENT OFFICE.

JOHN HENRY BENTLEY, OF MISTERTON, ENGLAND.

ROTARY KILN AND FURNACE.

Application filed September 9, 1926, Serial No. 134,545, and in Great Britain January 8, 1926.

- This invention relates to rotary kilns and furnaces of the type in which the heat extracted in cooling the material is used to pre-
heat the air and fuel supplied to the combus-
tion zone of the kiln or furnace, the object
of the invention being to provide improved
means for obtaining this recuperator effect
and to increase the output and reduce the fuel
consumption.
- In kilns used for burning cement materials
there is usually a drying or pre-heating zone
at the feed end followed by a calcining zone
and a sintering zone where combustion of the
fuel takes place adjacent to the discharge end.
- It is known to provide a preliminary cooling
chamber of greater diameter than the sintering
zone between that zone and a central dis-
charge orifice and according to the present in-
vention lifting ducts are fitted at the end of
such a cooling chamber and formed with
scoop-like openings at its circumference. A
delivery cone, provided by a conical or in-
clined guide closes the inner ends of the lift-
ing ducts to the interior of the kiln and opens
them to the exterior, and a recuperator cham-
ber is furnished below the discharge orifice
connected thereto by a pipe or cowl having a
packed joint around the orifice. Cascaders
may be provided in the cooling chamber.
- The recuperator chamber preferably con-
tains an inner cell surmounted by a conical
spreader (which may be fitted with spikes)
and the chamber is formed with a hopper-like
base. Cooling air is supplied to the cell and
issues therefrom through ports into an an-
nular passage between cell and chamber, and
if desired an encased conveyor may be pro-
vided below the base of the recuperator cham-
ber, cooling air being supplied to the cham-
ber also through the conveyor casing.
- Fuel is preferably blown into the kiln by a
fan or blower deriving its air from the recu-
perator chamber and connected to a pipe ex-
tending co-axially through the delivery cone
and through the preliminary cooling cham-
ber. Secondary combustion air passes into
the kiln from the recuperator chamber
through the lifting ducts which may be pro-
vided with apertures through their inner
walls to deliver this air nearer to the centre of
the preliminary cooling chamber. A renew-
able sleeve is conveniently fitted on the fuel
pipe adjacent to the delivery cone to protect it
from damage by the falling clinker.
- In the accompanying drawing:—

Figure 1 is a longitudinal section elevation
of the delivery end of a rotary kiln or furnace
according to the present invention.

Figure 2 is a half end view and transverse
section of Figure 1.

Like reference numerals indicate like parts
throughout the drawing.

The drying or pre-heating and calcining
zones of the kiln are not illustrated, Figure 1
showing the end of the sintering zone 3. Be-
yond this zone the kiln is continued with a
somewhat greater diameter to provide a pre-
liminary cooling chamber 4 which is closed at
the end by a suitable cover 5 having a central
discharge orifice as shown in Figure 1 and
being fitted with a circular track 6 supported
on rollers 7.

Cascaders 8 are shown inside the prelimi-
nary cooling chamber 4 arranged to lift the
material therein as they revolve with the kiln, 75
preferably only to such a height that the view
of the operator is not obscured through the
upper portion. The cascaders 8 do not extend
to the extreme end of the preliminary cooling
chamber 4, and in this cylindrical end por-
tion thereof is arranged a series of hollow lift-
ing ducts 9 rotating with the chamber. The
lifting ducts 9 are formed with scoop-like
openings at the circumference of the cham-
ber 4 and extend therefrom to a delivery cone 80
10 at the central discharge orifice, the delivery
cone 10 comprising conical or inclined guides
closing the inner ends of the lifting ducts 9
to the interior of the kiln and opening them to
the exterior.

The hollow lifting ducts 9 may be radial
to the cooling chamber 4 as shown in the sec-
tional half of Figure 2 or they may be curved
at their outer ends as shown in dotted lines
in the left-hand half of Figure 2. They may
either be radial or tangential or otherwise dis-
posed in relation to the delivery cone 10.
The openings of the lifting ducts 9 to the de-
livery cone 10 are separated from one an-
other by radial fins 11 of the cone, these fins 95
being a continuation of one or both of the
side walls of the lifting ducts or separate
therefrom as may be desired.

A stationary recuperator chamber 12 is
disposed at a lower level than the preliminary 105
cooling chamber 4, below its central discharge
orifice, and is connected to the latter by a suit-
able pipe or cowl 13 having a packed joint
as indicated at 14 around the delivery orifice,
the packing being such as to allow for the 110

expansion and contraction of the kiln as well as for its rotation.

The recuperator chamber 12 contains an inner cell 15 carried by girders 16 and surrounded by a conical spreader 17 which may be fitted with pointed spikes 18, the spreader being disposed in the path of material falling from the delivery cone 10 through the connecting pipe 13. Below the cell 15 the recuperator chamber is formed with a hopper-like base 19 by means of which the material is delivered through a suitable valve or damper 20 to a conveyor 21 or to an elevator, wagons or other suitable means of transport.

15 Cold air is supplied to the inner cell 15 by means of a blower or fan 22 through a pipe 23 and passes through ports or holes 24 in the lower portion of the cell into an annular space 25 between the cell 15 and walls of the recuperator chamber 12 which is preferably covered with a suitable heat insulating material (not illustrated). If desired a branch 26 from the fan pipe 23 may be connected to a casing 27 enclosing the conveyor 21 transporting the material from the base of the recuperator chamber 12, such air passing into the chamber through the valve 20.

The coal dust or other fuel is supplied through a pipe 28 and is blown into the kiln 30 by a fan or blower 29 deriving its air supply from the recuperator chamber 12 and connected to a pipe 30 which extends across the connecting pipe 13, through the delivery cone 10 with which it is co-axial and through the 35 centre of the preliminary cooling chamber 4 so that the fuel is burnt in the sintering zone 3. A renewable sleeve 31 is preferably fitted on the pipe 30 adjacent to the delivery cone 10 to protect it from damage due to the material falling thereon.

In operation the material may be treated in the rotary kiln as usual, but preferably its passage therethrough is retarded by conical portions as described in my specification No. 45 591 of 1926. On leaving the sintering zone 3 the material is cascaded in the preliminary cooling chamber 4 and gives up a portion of its heat to the air passing therethrough. On arriving at the extreme end it is lifted by 50 the hollow ducts 9 and delivered on to the discharge cone 10 whence it passes into the recuperator chamber 12 falling through the annular passage 25 provided by the inner cell 15 and being broken by the spikes 18 and the 55 spreader 17. During this fall it is meeting the upward stream of air from the interior of the cell 15 and from the base 19, and this air is thus heated and delivered into the preliminary cooling chamber 4 through the 60 hollow lifting ducts 9 whence it passes into the kiln to provide the secondary air for the combustion of the fuel, primary combustion air, of course, being derived also from the cooling chamber 12 and the amounts being controlled by dampers or throttle valves 32.

If desired the hollow lifting ducts 9 may be formed with apertures 33 for delivering the air nearer to the centre of the preliminary cooling chamber 4.

What I claim is:—

1. In a rotary kiln or furnace having a preliminary cooling chamber between the sintering zone and a central discharge orifice the combination with lifting ducts at the end of the cooling chamber having scoop-like openings at its circumference, of a delivery cone provided by a conical or inclined guide closing their inner ends to the interior of the kiln and opening them to the exterior, substantially as specified. 70

2. In a rotary kiln or furnace having a preliminary cooling chamber between the sintering zone and a central discharge orifice the combination with cascaders in the cooling chamber, of lifting ducts at the end 75 of the cooling chamber having scoop-like openings at its circumference, and a delivery cone provided by a conical or inclined guide closing their inner ends to the interior of the kiln and opening them to the exterior, substantially as specified. 80

3. In a rotary kiln or furnace having a preliminary cooling chamber between the sintering zone and a central discharge orifice the combination with lifting ducts at the end 95 of the cooling chamber having scoop-like openings at its circumference, of a delivery cone provided by a conical or inclined guide closing their inner ends to the interior of the kiln and opening them to the exterior and a recuperator chamber below the discharge orifice connected thereto by a pipe or cowl having a packed joint around the discharge orifice, substantially as specified. 100

4. The combination with a rotary kiln or furnace having a central discharge orifice of a recuperator chamber below such orifice connected thereto by a substantially gas tight passage and containing an inner hollow cell 110 surmounted by a conical spreader with an annular passage between cell and chamber extending to a hopper-like base of the chamber, means for supplying cooling air to the cell and ports putting the interior of the cell into communication with such annular passage, substantially as specified. 115

5. The combination with a rotary kiln or furnace having a central discharge orifice of a recuperator chamber below such orifice connected thereto by a substantially gas tight passage and containing an inner hollow cell 120 surmounted by a conical spreader with an annular passage between cell and chamber extending to a hopper-like base of the chamber, means for supplying cooling air to the cell, ports putting the interior of the cell into communication with such annular passage, an encased conveyor below the base of the chamber, a valve providing communication 125 between the said base and the conveyor and 130

means for supplying cooling air to the chamber through the conveyor casing, substantially as specified.

6. In a rotary kiln or furnace having a preliminary cooling chamber between the sintering zone and a central discharge orifice, the combination with cascaders in the cooling chamber, lifting ducts at the end of the cooling chamber having scoop-like openings at 10 its circumference, a delivery cone provided by a conical or inclined guide closing their inner ends to the interior of the kiln and opening them to the exterior, a recuperator chamber below the discharge orifice connected thereto by a pipe or cowl having a packed 15 joint around the discharge orifice, a hollow cell surmounted by a conical spreader inside the chamber with an annular passage between cell and chamber extending to a hopper-

like base of the chamber, means for supplying cooling air to the cell, ports putting the interior of the cell into communication with such annular passage, an encased conveyor below the base of the chamber, a valve providing communication between the said base 25 and the conveyor, means for supplying cooling air to the chamber through the conveyor casing, a fan deriving air from the recuperator chamber, a pipe connected to the fan and extending co-axially through the delivery 30 cone and through the preliminary cooling chamber and a renewable sleeve on such pipe adjacent to the delivery cone, substantially as specified.

In testimony whereof I hereunto affix my 35 signature.

JOHN HENRY BENTLY.
